(57) **CLAIM**

The ornamental design for a coffee maker as shown and described.

DESCRIPTION

FIG. 1 is a right side view of a first embodiment of a coffee maker showing my new design;

FIG. 2 is a left side view thereof;

FIG. 3 is a top plan view thereof;

FIG. 4 is a bottom plan view thereof;

FIG. 5 is a rear elevational view thereof;

FIG. 6 is a front elevational view thereof;

FIG. 7 is a top, left side perspective view thereof;

FIG. 8 is a top, right side perspective view thereof;

FIG. 9 is a top, front perspective view thereof;

FIG. 10 is a bottom, front perspective view thereof;

FIG. 11 is a rear, right side perspective view thereof;

FIG. 12 is a rear, left side perspective view thereof;

FIG. 13 is a right side view of a second embodiment of a coffee maker showing my new design;

FIG. 14 is a left side view thereof;

FIG. 15 is a top plan view thereof;

FIG. 16 is a bottom plan view thereof;

FIG. 17 is a rear elevational view thereof;

FIG. 18 is a front elevational view thereof;

FIG. 19 is a top, left side perspective view thereof;

FIG. 20 is a top, right side perspective view thereof;

FIG. 21 is a top, front perspective view thereof;

FIG. 22 is a bottom, front perspective view thereof;

FIG. 23 is a rear, right side perspective view thereof;

FIG. 24 is a rear, left side perspective view thereof;

FIG. 25 is a right side view of a third embodiment of a coffee maker showing my new design;

FIG. 26 is a left side view thereof;

FIG. 27 is a top plan view thereof;

(Continued)

FIG. 28 is a bottom plan view thereof;
 FIG. 29 is a rear elevational view thereof;
 FIG. 30 is a front elevational view thereof;
 FIG. 31 is a top, left side perspective view thereof;
 FIG. 32 is a top, right side perspective view thereof;
 FIG. 33 is a top, front perspective view thereof;
 FIG. 34 is a bottom, front perspective view thereof;
 FIG. 35 is a rear, right side perspective view thereof;
 FIG. 36 is a rear, left side perspective view thereof;
 FIG. 37 is a right side view of a fourth embodiment of a coffee maker showing my new design;
 FIG. 38 is a left side view thereof;
 FIG. 39 is a top plan view thereof;
 FIG. 40 is a bottom plan view thereof;
 FIG. 41 is a rear elevational view thereof;
 FIG. 42 is a front elevational view thereof;
 FIG. 43 is a top, left side perspective view thereof;
 FIG. 44 is a top, right side perspective view thereof;
 FIG. 45 is a top, front perspective view thereof;
 FIG. 46 is a bottom, front perspective view thereof;
 FIG. 47 is a rear, right side perspective view thereof;
 FIG. 48 is a rear, left side perspective view thereof;
 FIG. 49 is a right side view of a fifth embodiment of a coffee maker showing my new design;
 FIG. 50 is a left side view thereof;
 FIG. 51 is a top plan view thereof;
 FIG. 52 is a bottom plan view thereof;
 FIG. 53 is a rear elevational view thereof;
 FIG. 54 is a front elevational view thereof;
 FIG. 55 is a top, left side perspective view thereof;
 FIG. 56 is a top, right side perspective view thereof;
 FIG. 57 is a top, front perspective view thereof;
 FIG. 58 is a bottom, front perspective view thereof;
 FIG. 59 is a rear, right side perspective view thereof;
 FIG. 60 is a rear, left side perspective view thereof;
 FIG. 61 is a top, left side perspective view thereof, wherein the top panel is in an alternate position;
 FIG. 62 is a top, right side perspective view thereof, wherein the top panel is in an alternate position;
 FIG. 63 is a rear, right side perspective view thereof, wherein the top panel is in an alternate position;
 FIG. 64 is a rear, left side perspective view thereof, wherein the top panel is in an alternate position;
 FIG. 65 is a right side view of a sixth embodiment of a coffee maker showing my new design;
 FIG. 66 is a left side view thereof;

FIG. 67 is a top plan view thereof;
 FIG. 68 is a bottom plan view thereof;
 FIG. 69 is a rear elevational view thereof;
 FIG. 70 is a front elevational view thereof;
 FIG. 71 is a top, left side perspective view thereof;
 FIG. 72 is a top, right side perspective view thereof;
 FIG. 73 is a top, front perspective view thereof;
 FIG. 74 is a bottom, front perspective view thereof;
 FIG. 75 is a rear, right side perspective view thereof;
 FIG. 76 is a rear, left side perspective view thereof;
 FIG. 77 is a top, left side perspective view thereof, wherein the top panel is in an alternate position;
 FIG. 78 is a top, right side perspective view thereof, wherein the top panel is in an alternate position;
 FIG. 79 is a rear, right side perspective view thereof, wherein the top panel is in an alternate position; and,
 FIG. 80 is a rear, left side perspective view thereof, wherein the top panel is in an alternate position.
